UNITED STATES PATENT OFFICE

FRED J. KLINE, OF NEW YORK, N. Y.

PAPER FASTENER.

Application filed May 26, 1924. Serial No. 715,798.

To all whom it may concern:

Be it known that I, FRED J. KLINE, a citizen of the United States, residing in New York, in the county of Queens and State of 5 New York, have invented certain new and useful Improvements in Paper Fasteners, of which the following is a specification.

This invention relates to paper fasteners and particularly to three piece flat file paper 10 fasteners for holding letters, documents and various other papers.

The main object of the invention is to provide a fastener of this type which has improved means for securing the members 15 together. Another object is to provide a three piece paper fastener which is more easily and effectively operated than such fasteners which are now in common use. Still another object is to provide a paper 20 fastener of this type that is especially adapted to be made in various sizes and which is simple and economical in manufacture.

The means I prefer to employ for effecting these objects, together with various other 25 advantageous features of my improved paper fastener, are illustrated in the drawings accompanying and forming part of this specification, and in which—

Figure 1 is a plan of a paper fastener embodying my invention attached to a portion 30 of a file of papers.

Fig. 2 is a longitudinal section of the same taken on the line 2—2 of Fig. 1.

Fig. 3 is a transverse section of the same 35 taken on the line 3—3 of Fig. 1.

Fig. 4 is a plan of a modified form of my invention.

Fig. 5 is a longitudinal section of the same taken on the line 5—5 of Fig. 4.

Fig. 6 is a transverse section of the same 40 taken on the line 6—6 of Fig. 4.

Fig. 7 is a plan of a third form of my invention.

Fig. 8 is a plan of a fourth form of my 45 invention.

Fig. 9 is a longitudinal section of the same taken on the line 9—9 of Fig. 8.

Fig. 10 is a transverse section of the same 50 taken on the line 10—10 of Fig. 8.

Fig. 11 is an enlarged plan of a fifth form 55 of my invention.

Fig. 12 is a longitudinal section of the same taken on the line 12—12 of Fig. 11.

Fig. 13 is an enlarged plan of a sixth form 60 of my invention.

Fig. 14 is a longitudinal section of the same taken on the line 14—14 of Fig. 13.

Fig. 15 is a transverse section of the same taken on the line 15—15 of Fig. 13.

Fig. 16 is an end elevation of the retaining member of the same.

Fig. 17 is an enlarged plan of another form of my invention showing one of the intermediate positions of parts when applying the same.

Fig. 18 is a plan showing the final position of parts in the form of Fig. 17.

Fig. 19 is a plan of another modification.

Fig. 20 is an enlarged plan of a portion 65 of a paper fastener of the type of Figs. 17 and 18 showing means for locking the tongue covering member in its final position.

Fig. 21 is a partial longitudinal section of the same taken on the line 21—21 of Fig. 20, and

Fig. 22 is a plan of another modification 70 of my invention.

Like character of reference indicate like parts in all the figures of the drawings.

Referring to Figs. 1, 2 and 3, the numeral 80 1 indicates a member provided with two spaced apart tongues 2 connected by a main portion 3. The said tongues 2 are pushed through a file of papers 4 and then through slots 5 in a retaining member 6 and finally 85 bent down substantially horizontal on top of the member 6.

The member 6 has longitudinal ridges 7 near each of its side edges and projections or hooks 8 preferably struck up from the 90 material of the member 6 so that a tongue covering member such as 9 can be slipped under them in a suitable manner.

The said covering member is provided 95 with a bent down tongue 10 extending out lengthwise at the left hand end and is also provided with side slots or notches 11. To apply the tongue covering member 9, the tongue 10 is slipped into the left hand slot 5 in the retaining member 6 and pushed toward the left to the position shown in Fig. 2. The member 9 is then moved laterally so that the notch 11 at the middle part is slipped under the hook or projection 8 at the middle part of the member 6. Finally 105 the member 9 is moved laterally in the opposite direction so that the notch 11 at the right hand end is moved under the hook or projection 8 at the right hand end of the member 6. To remove the tongue covering 110

member 9 the above operations are reversed.

In the form shown in Figs. 4, 5 and 6, the members 1 and 6 are the same as in the form just described and are applied in the same way. The tongue covering member 9 is made without the tongue 10 and it has a slot or notch 14 near the left hand end to go under the left hand hook 8. To apply the member 9, it is placed obliquely on the member 6 between the left hand and middle hooks 8 and then turned laterally so as to go under the hooks. The movement is a gyrating one. The width of the member 9 is slightly less than the spacing of the inner portions of the hooks 8. This allows the member 9 to be moved laterally enough to slip its right hand end under the right hand hook 8 into the final position as shown in Fig. 4.

Fig. 7 shows a modification of the principle disclosed in Figs. 4, 5 and 6. In this form two notches 11^a are used and these are long and have abutments or shoulders 12 on only one end and relatively in reversed positions. The single hook 8 on the inner side of the member 6 is in this form nearer the left hand end than as shown in Fig. 4. The operation of placing the cover is similar to that in Fig. 4.

In the form shown in Figs. 8, 9 and 10, the hooks 8 on the member 6 are arranged as in the form shown in Fig. 4 with the addition of a fourth hook 8^a opposite the left hand one on the outer side. The member 9 has a bent down end portion 16 as more clearly shown in Fig. 9, and which is used to lock or secure the member 9 in its final position. The said member 9 can be inserted in two ways, one of which is to slide it lengthwise throughout its whole length until the portion 16 is snapped into the position shown in Fig. 9, and the preferred way is to first insert the left hand end of the member 9 under the hooks 8, 8^a, at the left, the width between bearing points of the hooks being greater than the width of the member 9, and then to move the member 9 laterally, first under the middle hook 8, and finally in the reverse direction under the right hand hook 8 and placing the portion 16 in the right hand slot 5 either by having it opposite the same in the last-mentioned movement or in finally moving it lengthwise of the fastener into said slot.

In the form of the fastener shown in Figs. 11 and 12, the member 1 is the same as in the previous forms but is shown somewhat shorter, and the member 6 has four oppositely-placed hooks 8. There is a downwardly-turned portion 16 on the covering member 9 to hold it in its final position. The said member 9 is ordinarily moved its entire length to place it in position under the hooks 8, and the portion 16 is brought to its final position by bending down the file

and the end portion of the member 6 as indicated in dotted lines in Fig. 12, and said portions are bent down in the same way to remove said member 9.

Figs. 13, 14, 15 and 16 show a form of the invention without side hooks in the retaining member 6. The tongue covering member 9 has a bent down portion or tongue 10 at its left hand end which is adapted to slip into the left hand slot 5 as shown in Fig. 14. The right hand end of the member 9 has a projection or tongue formed into a downwardly-extending hook 18 that is adapted to slip under the right hand end of the member 6, which is preferably provided with a recess 20 adapted to position it laterally.

In the form of fastener shown in Figs. 17 and 18, the member 6 has three hooks 8 on the inner side and two hooks 8 on the outer side, opposite the end hooks on the inner side. The member 9 is provided with an upwardly-turned portion 22 at one end to move it by. The said member 9 is placed in position by first sliding the left hand portion under the left hand hooks 8 as illustrated in Fig. 17, until the right hand end can move laterally inward past the outer right hand hook 8, thus bringing the member 9 under the inner middle hook. The said member 9 is then moved lengthwise under the right hand hooks 8 to the final position shown in Fig. 18.

The form of the invention shown in Fig. 19 operates in the same way as the form last shown, the difference between the two being that the greater length of the fastener of Fig. 19 allows the hooks 8 to be spaced slightly more advantageously as shown.

Figs. 20, 21 illustrate a downwardly-extending portion 24, which may be used in the last two forms, or in those of Figs. 4, 7, 8 and 11, in place of such portions as 16. An upwardly-turned portion such as 26 may also be formed in the retaining member 6 so that the portion 24 is not required to extend downward so far as it otherwise would. When the portion 24 is used with the form of fastener shown in Figs. 17, 18 and 19, the tongue covering member 9 must be a trifle longer than ordinarily made, so that the portion 24 shall come properly over the slot 5.

Fig. 22 illustrates a form of paper fastener in which the member 1 having the tongues 2 is similar to the foregoing forms and the retaining member 6 is similar to that of Fig. 11. The tongues 2 are shown in a condition where the file is of such thickness as to cause the projecting end portions of the tongues 2 to be very short and to come near the struck up hooks 8, so that it is very advantageous to form the tongue covering member 9 with portions 30 at each end, narrower than the remaining portion of the

member, and said portions 30 are especially adapted to be passed in between the hooks 8, over the ends of the tongues 2, before the main portion 31 has come between said hooks 8. Thus it is much easier to assemble the member, especially when the tongues 2 are unevenly bent or rendered uneven on account of use.

What I claim is:—

- 10 1. A paper fastener embodying a member having a main portion and spaced apart tongues to be pushed through papers at right angles thereto, a retaining member having slots through which the projecting tongue portions can then be passed and bent down on said member, and means for holding a covering member, a tongue covering member adapted to be held by said means, and means whereby the tongue covering member is secured in position on the retaining member by relative movements between said members and which movements include a laterally gyrating one and a limited longitudinal movement.

- 25 2. A paper fastener embodying a member having a main portion and two spaced apart tongues to be pushed through papers at right angles thereto, a retaining member having two slots through which the projecting tongue portions can then be passed and bent down on said member and having means to movably hold a tongue covering member, a tongue covering member adapted to be held by said means, and means to lock said tongue covering member in its final position.

- 35 3. A paper fastener embodying a member having two spaced apart tongues to be pushed through papers, a retaining member having two slots through which the projecting tongue portions can then be passed and bent down on said member and a plurality of staggered holding elements spaced along its length and including two upwardly-projecting ones, and a tongue covering member adapted to be held by said elements and means adjacent to its end to lock it in its final position.

4. A paper fastener embodying a member having two spaced apart tongues to be pushed through papers, a retaining member having two slots through which the projecting tongue portions can then be passed and bent down on said member and a plurality of staggered holding elements spaced along its length and including two upwardly-projecting hooks on opposite sides respectively, and a tongue covering member adapted to be held by said holding elements.

5. A paper fastener embodying a member having two spaced apart tongues to be pushed through papers, a retaining member having two slots through which the projecting tongue portions can then be passed and bent down on said member and having a plurality of staggered holding elements

spaced along its length, and a tongue covering member adapted to be held by said elements and movable into its final position by relative lateral movement between itself and the retaining member.

6. A paper fastener embodying a member having two spaced apart tongues, a retaining member having two slots through which the projecting tongue portions can then be passed and bent down on said member and means to secure a tongue covering member which include an upwardly turned hook at one side near one end and an upwardly turned hook on the opposite side substantially midway, and a tongue covering member adapted to be held by said means and to be passed into the same by relative movements between said members and including a laterally gyrating movement.

7. A paper fastener embodying a member having spaced apart tongues to be pushed through papers, a retaining member having slots through which the projecting tongue portions can then be passed and bent down on said member and having a plurality of hooks whereby a tongue covering member can be held, there being at least one of said hooks on each side of said retaining member, and a tongue covering member adapted to be held thereby and to be locked in its final position by a relative lateral movement between the tongue covering member and the retaining member.

8. A paper fastener embodying a member having two spaced apart tongues to be pushed through papers, a retaining member having two slots through which the projecting tongue portions can then be passed and bent down on said member, a tongue covering member adapted to be held over the bent down tongue portions, and means whereby the tongue covering member is held in such position and into which it is moved and locked by a combination of movements including a longitudinal one and a laterally gyrating one.

9. A paper fastener embodying a member having two spaced apart tongues to be pushed through papers, a retaining member having two slots through which the projecting tongue portions can then be passed and bent down on said member, a tongue covering member adapted to be secured in position over the bent down tongue portions, and means including two upwardly-disposed hooks one on each of the two sides of said retaining member whereby the tongue covering member is held in such position and into which it is moved by a combination of movements including a longitudinal one and a laterally gyrating one.

10. A paper fastener embodying a member having two spaced apart tongues to be pushed through papers, a retaining member having two slots through which the pro-

jecting tongue portions can then be passed and bent down on said member, a tongue covering member adapted to be held over said bent down tongue portions, and means 5 including a plurality of projections on one of said members, one being a hook adapted to engage with the edge of the other of said members and whereby the covering member is held in such position and into which it is 10 moved and locked by a combination of movements including a longitudinal one and a laterally gyrating one.

11. A paper fastener embodying a member having two spaced apart tongues to be 15 pushed through papers, a retaining member having two slots through which the projecting tongue portions can then be passed

and bent down on said member, a tongue covering member adapted to be held over said bent down tongue portions, and means 20 whereby said tongue covering member is held in such position which include two pairs of oppositely-disposed hooks on the retaining member and a locking projection on the tongue covering member and into which 25 position said tongue covering member is passed by a combination of movements including a longitudinal one and a laterally gyrating one.

Signed at New York, in the county of 30 New York, and State of New York, this 7th day of May, 1924.

FRED J. KLINE.
